UNITED STATES PATENT OFFICE.

LAWRENCE DE VRIES, OF ZEELAND, MICHIGAN.

BEET-HARVESTER.

1,045,819.

Specification of Letters Patent.

Patented Dec. 3, 1912.

Application filed April 8, 1912. Serial No. 639,194.

To all whom it may concern:

Be it known that I, LAWRENCE DE VRIES, a citizen of the United States of America, residing at Zeeland, in the county of Ottawa 5 and State of Michigan, have invented certain new and useful Improvements in Beet-Harvesters; and I do hereby declare the following to be a full, clear, and exact description of the invention, such as will enable 10 others skilled in the art to which it appertains to make and use the same.

My invention relates to improvements in beet harvesters and its object is to provide a machine that will remove the tops from the 15 beets, deposit the tops at one side of the row, and lift the beets out of the ground, and to provide the same with various new and useful features hereinafter more fully described and particularly pointed out in the claims, 20 reference being had to the accompanying drawings, in which:

Figure 1 is an elevation of a machine embodying my invention as it appears when in use; Fig. 2 is a plan view of the same; Fig. 25 3 an enlarged sectional detail in vertical section; Fig. 4 an enlarged detail in elevation showing the hub of the rake and parts adjacent; Fig. 5 a plan view of the same; Fig. 6 a further enlarged detail of a rake arm in 30 transverse section and Figs. 7 and 8 elevations showing details of the means for mounting the cutter.

Like numbers refer to like parts in all of the figures.

35 1 represents the frame of the machine consisting substantially of parallel flat bars converging at the front and adapted to be attached to means for moving the machine.

40 2 are handles for manually guiding the machine.

3 and 6 are vertically disposed tubular posts secured to the frame 1 by clips 4 and plates 5 and vertically adjustable.

7 is a horizontally disposed cutting blade 45 inclined across the path of the machine to secure a drawing cut on the tops of the beets to more readily sever the same. Each end of this blade is secured to a standard 23 vertically slidable in the respective posts 3 and 6 and yieldingly supported therein by a contractile spring 25 secured to the upper end thereof at the lower end, and to an adjustable support 26 at the upper end. The blade 7 is turned upward at right angles at 55 each end and pivotally secured as at 25 in a transverse slot in the standard 23 and to ad-

just the edge of the blade vertically, an angle plate 8 is secured to the standard above the blade and carries adjusting screws 24 whereby the blade can be adjusted about the pivot 25 to raise and lower the cutting edge thereof as illustrated in Figs. 7 and 8.

To remove the tops and deposit the same between the rows a rake is provided preferably constructed as follows: Upon the post 6 are collars 27 and 28 spaced apart, between which the hub of the rake is rotative on the post and is rotated by bevel gears 17 one of which is on the hub and the other on a shaft 16 extending across the frame and journaled 70 in the collar 27 at one end and a suitable hanger attached to the frame at the other end. On the outer end of this shaft is a sprocket wheel 17^a from which extends a chain 18 and engages a similar sprocket 75 wheel 19 attached to a wheel 9 which is mounted on the post 3 to carry one side of the machine, the other side being carried by a like wheel mounted on the post 6.

Concentric with the hub of the rake is a 80 rim 11 carried by fixed radial arms or spokes 12 between which are radially disposed rock shafts 13 supported by the rim at one end and by the hub at the other end. On each of these rock shafts is mounted a rake 85 composed of a series of teeth 15 preferably of steel rods which terminate when turned downward close to the earth to properly engage and remove the severed tops of the beets. These teeth are each coiled around 90 a rock shaft and terminate radially above the same where they are inserted in a plate 14 bolted to the rock shaft. They are thus held from rotating on the rock shaft and in spaced relation. Each rock shaft is provided near its inner end with upward and downward projections 31 and a cam plate 29 fixed on the upper collar 27 is engaged by the upward projection 31 to turn the rake teeth 95 downward to engage and move the tops of the beets during that part of the revolution of the teeth around the post 6 in which they are passing between the posts 3 and 6 and across the row of beets. 30 is a similar cam plate engaged by the downward projection 100 31 on each rock shaft whereby the rake teeth are turned upward to release the beet tops and leave the same between the rows and also to retain the teeth in this elevated position until again turned downward.

To lift the beets out of the ground standards 20 extend downward from the rear of

the frame carrying at their lower end wedge shaped members extending substantially parallel and spaced apart, being slightly diverging rearward and inclined upward on 5 their upper surfaces. They are drawn through the soil by the standards loosening the soil and lifting the beets, and at the rear of these wedges are fingers 22 which permit the soil to fall between the same and separate the beets therefrom, leaving the beets 10 on the surface of the soil.

What I claim is:

1. A beet harvester, comprising a frame, a blade extending beneath the frame and 15 having upturned ends, standards carried by the frame to which the said upturned ends are pivoted, an angle plate fixed on a standard above the blade and screws in the horizontal member of the plate to engage and 20 adjust the blade.

2. A beet harvester, comprising a frame, tubular posts attached to the frame, standards vertically slideable in the posts, springs 25 adjustable in the posts and supporting the standards, a blade horizontally disposed and having upturned ends pivoted to the standards, angle plates attached to the respective standards above the blade and adjusting screws in each plate engaging the 30 blade.

3. A beet harvester, comprising a frame, tubular posts adjustably attached to the frame, supporting wheels mounted on the respective posts, a standard vertically slideable in each post, a spring in each post supporting a standard, a horizontally disposed blade having upturned ends pivoted in each standard and means for adjusting said blade about its pivots.

40. 4. A beet harvester, comprising a frame, posts attached to the respective opposite sides of the frame, a horizontally disposed blade carried by the posts, a supporting wheel on each post, a rake rotative about one 45 of the posts, means for rotating the rake connecting the rake and one of said wheels, radial rock shafts in the rake, rake teeth projecting downward from the shafts, means

for turning the shafts to lower the teeth during a part of their revolution about the 50 post and means for turning the shafts to raise the teeth during another part of said revolution.

5. A beet harvester, comprising a frame, wheels supporting the frame, posts on which the wheels are mounted, collars on one post spaced apart, a hub rotative on the post between the collars, radiating spokes and a rim carried by the hub, radial rock shafts carried by the hub and rim, rake teeth fixed 60 on the shafts and projecting downward therefrom, a cam on each collar and projections on each shaft to alternately engage the respective cams and shift the rock shafts.

6. A beet harvester, comprising a frame, posts attached to the frame, a supporting wheel mounted on each post, a blade carried by the posts to sever the tops of beets, collars mounted on one of the posts and spaced apart, a hub rotative between the collars, a shaft connected to one of the wheels whereby the shaft is rotated, gears connecting the shaft and hub, radially disposed rock shafts carried by the hub, rake 70 teeth on each rock shaft, opposing projections on each rock shaft, a cam on one collar to engage one of the projections on each shaft and turn the rake teeth downward during a part of the revolution of the hub 75 and a cam on the other collar to engage the other projections and turn the rake teeth up during another part of the said revolution.

7. A beet harvester, comprising a rotative hub, a radially disposed rock shaft carried 85 by the hub, means for rotating the hub, rods forming rake teeth each coiled around the shaft near the upper end and a plate secured to the shaft and having openings in which the ends of the rods are inserted.

In testimony whereof I affix my signature in presence of two witnesses.

LAWRENCE DE VRIES.
